UNITED STATES PATENT OFFICE.

SYDNEY JAMES WALLACE DAVIDSON, OF AUCKLAND, NEW ZEALAND.

GAS RING OR BURNER.

1,375,572.

Specification of Letters Patent. Patented Apr. 19, 1921.

Application filed March 29, 1920. Serial No. 369,733.

To all whom it may concern:

Be it known that I, SYDNEY JAMES WALLACE DAVIDSON, a citizen of the Dominion of New Zealand, and residing at Scarborough Terrace, Parnell, Auckland, in the Provincial District of Auckland, a subject of the King of Great Britain and Ireland, have invented certain new and useful Improvements in Gas Rings or Burners, of which the following is a specification.

This invention relates to means employed in generating heat from spirit oil such as petrol, gasolene, kerosene, benzolin and the like.

The object of the invention is to provide an improved device, capable of being used either as a gas ring or as a burner on a stove, griller or other heating apparatus.

According to the invention the device comprises a body with an outwardly and upwardly sloping flange, around the upper edge of which is a wall.

A central tube projects upward through the body and is surrounded by a loose ring having an internal flange around its upper edge and formed with equally spaced cross grooves in its lower edge.

The ring is recessed into the body, and a loose cap having a central inverted cone projecting downward from the under surface and formed with equally spaced cross grooves in its lower edge, is recessed in said ring.

A circular recess is provided in the body at the bottom of the sloping flange and in said recess a correspondingly shaped tube is placed, the latter having two connections passing downward through the body.

From one of said connections a hollow conductor leads to a nipple holder, the nipple of which is directed upward beneath the tube passing through the body, the other of said tubes being connected to a fuel supply wire of a hollow wire system.

The inlet connection of the circular tube is preferably packed with wire bound asbestos, cord or the like.

The invention will be more particularly described with reference to the accompanying drawing, in which:

Figure 1 is a sectional elevation of the device, and

Fig. 2 a plan view of same, with the ring and cap removed, while

Fig. 3 illustrates in perspective the circular tube and connections,

Fig. 4 the wire bound asbestos core,

Fig. 5 the ring which surrounds the central tube of the body, and

Fig. 6 an alternative shape for the wall 60 around the sloping flange.

The body 1 is formed with a tube 2 passing upward through same, the internal diameter of said tube preferably decreasing upward.

Surrounding said tube is a beveled ring 3 formed with an internal flange 4 around its upper edge, and equally spaced cross grooves 5 in its lower edge. The ring 3 sits inside a vertical flange 6 on the body 1, so that the grooves 5 show slightly above the latter, while the flange 4 is recessed to take a beveled cap 7.

On the under surface of the cap 7 is an inverted cone 8 which is located centrally over the tube 2, and in the lower edge of said cap are equally spaced cross grooves 9 which show above the upper edge of the ring 3.

The sloping flange 10 extends outward 80 and upward from the body 1 and is surrounded by a wall 11 either vertical or concave as shown.

At the bottom of the flange 10 the circular tube 12 which serves as the main generator 85 of the device, is sunk in a recess 13 and from the tube 12 diametrically opposite threaded connections 14, 15 pass downward through the body 1.

From the connection 14 a hollow conductor 16 leads to the nipple holder 17, the nipple 18 of which is directed upward and is located centrally below the tube 2.

The other connection 15 is connected with a fuel supply wire 19 preferably fitted with a control cock 20.

The connection 15 is packed with the wire bound asbestos core 21.

The device is provided with legs 22 which extend upward sufficiently to provide rests 100 for a utensil such as a kettle, or the like.

When used as a burner on a stove or the like, the legs 22 are dispensed with.

In use and with the control cock 20 open, the liquid fuel under pressure, is directed by 105 the wire 19 and connection 15 to the tube or main generator 12.

The effect of inserting the core 21 in the connection 15 is that no body of liquid fuel enters the generator 12, the fuel entering the latter in the form of vapor. From the main generator 12 the fuel passes by way of the

connection 14 and conductor 16 to the nipple holder 17 and nipple 18, to which heat is applied temporarily until gas is generated. The gas generated enters the tube 2 from the 5 nipple 18 and is split up and deflected by the inverted cone 8, to the grooves 5 and 9 of the ring 3 and cap 7, whereupon it is ignited, the resultant flame jets being directed by the flange 10 and wall 11 upward against 10 the bottom of a utensil placed on the rests 23.

Owing to the close proximity of the tube 12 to the flame jets from the grooves 5 and 9, the former is heated and generation of gas is set up therein as the fuel passes through 15 said generator, generation continuing automatically until the fuel supply is cut off.

The effect of the splitting up of the gas by the inverted cone 8 is that back firing of the device is prevented, also the wall 11 confines 20 the flame jets to the limit of the utensil being heated.

As will be observed the device with the exception of the rings 3 and cap 7 is made in one piece, and by disconnecting the connections 14, 15 from the conductor 16 and wire 19, the generator 12 is readily removable for 25 inspection or replacement.

What I claim and desire to secure by Letters Patent of the United States of America is:—

1. A device for the purpose set forth, comprising a body portion with a central tube projecting vertically through same; a ring with cross grooves in its lower edge around the upper end of said tube; a cap with cross grooves in its lower edge engaged on said ring; a sloping flange around said body; a circular generator removably seated at the bottom of said sloping flange; a gas pipe depending from the generator, an upwardly directed nipple located centrally below said tube and in communication with said generator through said pipe; and a fuel supply for the generator.

45 2. A device for the purpose set forth comprising a body portion with a central tube projecting vertically through same; a ring with cross grooves in its lower edge around the upper end of said tube; a cap with cross grooves in its lower edge on said ring; a sloping flange with a wall at its top around 50 said body portion; a circular generator re-

movably seated at the bottom of said sloping flange; opposed extensions carried by the generator received in the body, and a nipple 55 connected with one of said extensions and arranged centrally below the central tube.

3. A device for the purpose set forth comprising a body portion with a central tube passing vertically therethrough; a ring with 60 cross grooves in its lower edge around the upper end of said tube, a cap with cross grooves in its lower edge seated in said ring, and a conical deflector carried by the cap projecting into the tube.

4. A device for the purpose set forth comprising a body portion with a central tube projecting vertically therethrough; a ring with cross grooves in its lower edge and an internal flange around its upper edge, sitting 70 within a flange on said body portion and around said tube; and a cap with cross grooves in its lower edge and an inverted cone on its under surface, recessed in said ring.

5. A device for the purpose set forth comprising a body, a ring with cross grooves in its lower edge and an internal flange around its upper edge and supported on said body, a cap with cross grooves in its lower edge 80 and an inverted cone on its under surface and recessed in said ring.

6. A device for the purpose set forth comprising a body, a removable circular tube recessed therein; a burner surrounded by said 85 tube; an outwardly and upwardly sloping flange with a wall at the top surrounding said generator, and hollow extensions carried by the tube removably positioned through the body and constituting a fuel 90 inlet to said tube and a gas outlet therefrom.

7. A device for the purpose set forth comprising a circular tube; a burner surrounded by said tube, a fuel inlet connection for the tube, a core arranged in said connection to 95 restrict the flow of liquid therethrough, and a gas outlet connection for said tube.

In testimony whereof I affix my signature in presence of two witnesses.

SYDNEY JAMES WALLACE DAVIDSON.
